LIQUID FUEL PUMP

Lewis Pengilly, Palo Alto, Calif.

Application July 12, 1943; Serial No. 494,298

5 Claims. (Cl. 103—164).

1

This invention relates to a liquid elevating device designed primarily as a fuel pump for an internal combustion engine.

One object of the invention is to provide a new and improved device for elevating liquid, and including a pump adapted to produce pulsation of an air column connecting the pump with a source of liquid supply.

Another object of the invention is to provide a simple and economically constructed pumping device adapted for continuous operation in connection with an engine for supplying liquid fuel thereto and arranged to transmit pumping impulses to a valve structure in the fuel tank by means of an air column connecting said structure with the pumping device.

It is also an object of the invention to provide a liquid elevating apparatus which includes a valve structure submerged in a supply of liquid with a delivery pipe leading therefrom; and with an air pipe leading into said structure together with a pump connected to deliver a series of pressure impulses to said air pipe with alternating suction impulses, and means rendering the impulses effective principally in one direction for causing elevation of the liquid into the delivery pipe.

A further object of the invention is to provide a pumping device of simple construction, together with piping and check valves arranged for lifting liquid fuel to an engine carburetor and adapted for continuous operation by the engine; but arranged to automatically cease supplying said fuel when the carburetor is full, and to automatically replenish the supply when the level of fuel in the carburetor falls.

Other objects and advantages of the invention will appear from the following description taken in connection with the drawings in which:

Fig. 1 is a schematic layout of an internal combustion engine and a fuel tank therefor, together with pumping mechanism and piping constructed in accordance with this invention.

Fig. 2 is a vertical sectional view taken principally through the axis of the pump cylinder and showing the pump on an enlarged scale.

Fig. 3 is a fragmentary elevation partly in section through the valve chamber assembly located in the fuel tank.

Fig. 4 is a vertical sectional view similar to Fig. 2, showing a modified pump construction.

Fig. 5 is a vertical sectional view showing another modification of the pump structure.

Fig. 6 is a second schematic layout showing an internal combustion engine and fuel tank there-

2

for, together with a modified valve assembly in the tank and a modified pump at the engine.

Fig. 7 is a vertical sectional view showing the pump on an enlarged scale as compared with Fig. 6.

Fig. 8 is a vertical sectional view of the valve chamber and associated parts located in the fuel tank, showing this structure on an enlarged scale.

Fig. 9 is a vertical sectional view of an air inlet valve arranged in the air line of Fig. 6.

While there is shown and described herein certain specific structure embodying the invention, it will be manifest to those skilled in the art that various modifications and rearrangements of the parts may be made without departing from the scope of the invention, and that the same is not limited to the particular forms herein shown and described, except in so far as indicated by the appended claims.

This application is a continuation-in-part of my application Serial No. 409,942, filed September 8, 1941, patented June 13, 1944, No. 2,351,064.

In the construction illustrated in Figs. 1, 2 and 3, an internal combustion engine is designated generally by the numeral 1, and a tank containing a supply of liquid fuel, therefor is shown at 2 in cross-section. The engine has a carburetor 3 which includes the usual fuel bowl and float valve within the bowl. The carburetor 3 is connected by a fuel delivery pipe 4 to a valve chamber assembly 5 located within the fuel tank 2 near the bottom thereof, so as to be normally submerged by the liquid fuel.

A pump 6 is associated with the engine 1 so as to be driven continuously thereby when the engine is running, as, for example, by means of an eccentric 6^a, which may be secured to the usual cam shaft of the engine, the pump having a pitman 6^b arranged to be oscillated by said eccentric.

The pump 6 is connected by an air pipe 7 to the valve chamber assembly 5 in the tank 2, and said pump includes a cylinder 8 with a piston 9 arranged to be reciprocated therein by means of the pitman 6^b. The piston 9 is shown with an annular groove 10 at a selected position between the top and bottom of the piston, and with a passage 11 extending from the groove or channel 10 to the upper end of the piston, as seen in Fig. 2.

The cylinder 8 is provided with two spaced ports 12 and 13 in its side wall, the upper port 12 being an air inlet and the lower port 13 being a pressure outlet to which the pipe 7 is connected for delivery of air impulses to the valve assembly 5 in the fuel tank. A passage 14 connects the

ports 12 and 13, as shown, and the air inlet port 12 is provided with an inwardly opening check valve 15 which is held normally closed by means of a spring 15^a. The seat member 15^b for said valve 15 is threaded for axial adjustment whereby the tension of the spring 15^a may be varied as desired.

The valve chamber 5 includes vertically spaced check valves 16 and 17 therein, the valve 16 opening inwardly with respect to the interior of the chamber, and the valve 17 opening outwardly with relation thereto and controlling the delivery of liquid from the chamber 5 to the fuel delivery pipe 4, which has a terminal portion 4^a within the chamber 5. Both the valves 16 and 17 are normally held seated by springs, as shown in Fig. 3, and the fuel inlet controlled by the valve 16 is preferably provided with a filter screen 18.

Whenever the engine 1 is running, the piston 9 reciprocates in the pump cylinder 8. On the down-stroke of the piston 9, suction is created in the cylinder head until the channel 10 in the piston registers with the port 13, thus momentarily applying the suction through the passage 11 and through the air-line 7 to assist in lifting the bottom check valve 16 in the chamber 5 and allowing fuel to flow into the chamber; but the force of this suction is limited by the adjustment of the spring 15^a which holds the check valve 15 seated, and said valve will open to admit air at atmospheric pressure whenever the force of the suction exceeds the strength of the spring 15^a. On the up-stroke of the piston 9, however, the valve 15 remains seated, and the stroke is employed to compress air in the upper portion of the cylinder 8. When the groove or channel 10 registers with the port 13, this pressure is applied suddenly to the air column in the pipe 7, forcing the check valve 17 to open and lifting a portion of the fuel in the chamber 5 upwardly and past said check valve, into the delivery pipe 4.

The action just described is repeated with successive strokes of the piston, with the result that the fuel is elevated, step by step, through the pipe 4, and delivered to the carburetor 3.

The spring on check valve 16 is relatively light, so that when the pump is not in operation, the valve chamber 5 and the lower end of the delivery pipe 4 will tend to fill with liquid, to a height substantially equal to the level of liquid in the tank 2. However, when the fuel is being consumed rapidly by the engine 1, the intermittent suction in the pipe 4 is helpful in insuring opening of the valve 16 to maintain a sufficient amount of fuel within the chamber 5.

The provision of the air inlet port 12 and check valve 15 operates to limit the suction produced by the pump to considerably less than that corresponding to a full piston stroke, and this suction is at no time sufficient to lift the liquid into the air-line 7 to a height more than slightly above the level of fuel in the tank. Even if the carburetor is filled, and its float valve prevents the further delivery of fuel through the pipe 4, the continued operation of the pump will not suck the fuel above the said level in the pipe 7. However, as a precaution, and particularly when the system is installed on a vehicle which may not always travel on a level road, I prefer to provide an inverted siphon in the air-line 7 by extending the pipe for some distance above the fuel tank the distance through which the suction effect in excess of that through which the siphon could be operative, as shown at 7^a in Fig. 1.

Since the cylinder 8 is thus vented to the atmosphere before the piston completes its full suc-

tion stroke, whereas, in the opposite direction, the piston operates through its full stroke to deliver a pressure impulse to the air-line 7, the result is a succession or series of impulses, which are effective principally in one direction, along the air-line 7, and for elevating liquid from the chamber 5 into the delivery pipe 4. Particularly when the pump operates at relatively high speed, as it does in connection with an internal combustion engine of the automotive type, there is a tendency for some of the air in the pipe 7 to be passed into the liquid in the chamber 5 and to be discharged therewith. This would operate to rarefy the air in the line 7, but any such loss of air is at once replaced by way of the check valve 15 and passage 14 during the suction stroke of the piston, because with the air in the pipe 7 rarefied to any extent, the suction produced by the piston will reach a higher value than the spring 15^a can resist, and atmospheric pressure acting upon the valve 15 will open it to supply air to replace that which has been mixed with the liquid fuel and delivered from the chamber 5 therewith.

Fig. 4 shows a modified form of pump in which the cylinder 20 is connected to the air-line 7 through an outlet port 21. The piston 22 is formed with a passage 23 extending from the top wall of the piston and through the side wall thereof for registration with an air supply port 24 in the side of the cylinder 20 when the piston reaches the lower limit of its stroke. Thus, at each suction stroke, atmospheric air is supplied to the cylinder in whatever quantity is required to replace any loss from the air-line 7, and each pressure stroke is thus fully effective to provide the desired pulsation in the air column in the pipe 7 for lifting the check valve 17 and passing fuel from the chamber 5 into the delivery pipe 4. With this arrangement, no check valve need be provided in the air intake for the cylinder 20, since the port 12 is never uncovered, except at the extreme limit of piston travel, and this port is closed substantially at the beginning of the pressure stroke.

Fig. 5 shows a modified form of pump suitable for mounting in the side wall of the engine crank case adjacent the position of the cam shaft 25 therein, which is shown with an eccentric 26 operating against a stem 27 on the end of the piston. The cylinder 28 is indicated as integral with the side wall 29 of the engine casting, and is provided with an applied head 30 having a central port 31 into which the air-line 7 is connected. The head 30 includes a pocket 32 which may be of smaller diameter than the interior of the cylinder 28, and accommodates a spring 33 coiled about a guide extension 34 on the end of the hollow piston 35, the spring 33 serving to maintain contact of the stem 27 with the operating eccentric 26. This pump may be provided with air inlet facilities, either of the type shown in Fig. 2 or in accordance with the arrangement shown in Fig. 4, but, as illustrated in Fig. 5, the piston 35 is not provided with any port or passage, as in said structures, and is intended for use with an air supply valve arranged in the line 7 in a manner about to be described.

Fig. 6 shows a layout somewhat similar to that of Fig. 1, but in which the particular pump illustrated is of modified construction, and the valve chamber in the fuel tank also includes some features not found in that of Fig. 3; and in this arrangement the air lost by admixture with the fuel in the pumping operation is replaced by means of an air inlet valve connected into the

air-line 7, as shown at 40. An engine is conventionally illustrated at 41, with a fuel supply tank at 42 and a carburetor at 43. A delivery pipe 44 extends from the valve-chamber assembly 45, and a pump is shown at 46 applied to the side wall of the crank case for actuation by a cam or eccentric 47 on the cam shaft of the engine.

The pump 46 is shown in Fig. 7 as including a cylinder 48 having an outlet 49, at one end of which the air-line 7 is connected. The flange 50 at the other end of the cylinder is bolted to the side wall of the engine, indicated at 41, and at this end of the cylinder there is provided a guide 51 for the piston rod 52, which is secured in the end wall of the piston 53. A spring 54 is coiled about the outer end portion of the piston rod 52 and reacts between said guide 51 and a head 55 on the rod. The head 55 is engaged by a eccentric 56 on the cam shaft 57 of the engine, as seen in Fig. 7, but the stroke of the piston is limited by means of a stop collar 58 on the piston rod 52, said collar abutting the guide member 51 to provide clearance at 59 between the head 55 and the eccentric 56. This allows a brief interval at the end of the stroke, permitting the valves in the fuel elevating device to operate to better advantage, so as to perform more efficiently at high speed.

The pumping chamber 45, which is shown in detail in Fig. 8, includes an inlet valve 60 seating outwardly with respect to the chamber, and an outlet valve 61 seating inwardly with respect to said chamber. These valves are held normally seated by their springs, as seen in Fig. 8, and the pressure impulse transmitted through the pipe 7 operates to open the valve 61 and to pass liquid fuel from the chamber 45 above the valve, in the same manner as with the structure of Fig. 3. But to improve the operation an air dome 62 is formed in the assembly surrounding the terminal portion 64 of the delivery pipe 4, said terminal portion being shown as an integral part of the cast chamber 45. Any air which is admixed with the liquid fuel, either in the tank or by virtue of the application of the air column in the line 7 to the liquid in the chamber 45, tends to free itself from the liquid as the latter passes the valve 61, and to accumulate in the air dome 62. This provides an air cushion against which the pumping pressure operates, and which helps to force the liquid upwardly through the delivery pipe 4 and to maintain a reasonably uniform flow therethrough, damping out the pulsations produced by the operation of the pump at 46.

Replacement of air lost from the air-line 7 in the pumping operation is effected by means of the check valve device 49, which includes a gravity seated disk valve 70 and an air inlet port 71 provided with a regulating screw 72 by which the capacity of the port may be varied, as may be found desirable in view of the particular installation of the apparatus. Thus, upon each suction stroke of the pump 46, if the air column in the pipe 7 has been depleted by leakage or by loss of air absorbed in the liquid fuel, this leakage or loss will be replaced by the automatic opening of the check valve 70, admitting air through the port 71 during the brief suction interval.

This substantially continuous addition of air to the line 7 may sometimes tend to build up a pressure in the line in excess of that which is desirable, and such pressure is automatically relieved by means of a valve 65 which forms the

lower end wall of the chamber 45. The valve disk is seated upon a supporting disk 66 carried by a spring 67, which is shown conveniently disposed in an annular space around the inlet screen 68. A central opening in the disk 66 is defined by an upwardly projecting annular flange 69 which forms the inlet passage and provides the seat for the inlet valve 60. With this arrangement, whenever the pressure in the line 7 exceeds the tension of the spring 67, this pressure transmitted through the chamber 45 will depress the relief valve 65 so that the excess of air may escape through the screen 68 into the tank. This will tend to produce some turbulence in the liquid adjacent the inlet to the chamber 45, with the result that the air in this vicinity will find its way to the air dome 62 as the liquid is pumped up into the chamber 45, and will thus serve to maintain the desired air cushion in the dome 62 for facilitating the flow of liquid through the pipe 4.

With reference to the clearance shown at 59 in Fig. 7, between the cam 56 and the head of the piston rod 52, it will be understood that the delay interval effected by means of this clearance might also be secured by making the corresponding portion of the cam concentric with its axis of rotation. There is also shown in Fig. 7, near the right-hand end of the pump cylinder 48, a restricted port 48a formed in the side wall of the cylinder and positioned to be uncovered by the piston at the end of its suction stroke. If the check valve 40 is employed, this port will ordinarily be plugged up; but, if preferred, this inlet port may be utilized in place of the air inlet check valve 40 to insure replacement of such air as may be lost from the air column in the pipe 7 by absorption in the liquid fuel, or otherwise.

In most pumping devices of this general character for moving liquid fuel, the difficulty commonly known as "vapor lock" is frequently encountered; but in the structures herein disclosed this trouble has been overcome partly by the automatic replenishment of air as required in the pressure line 7, and also by virtue of the relief valve provided at 65, which avoids the accumulation of excessive pressure in the line. Frequent operation of the air inlet valve 15 or 70 and of the valve 65 tends to disturb or agitate the air column sufficiently to insure its proper functioning at all times.

I claim:

1. In a liquid elevating system which includes a liquid supply, a chamber having an inlet submerged therein and a delivery pipe leading upwardly therefrom, said chamber comprising an outer cylindrical body having a top wall, an inner cylinder suspended in the outer cylinder in spaced relation thereto and having an outlet port in its lower end, a delivery tube connected with said delivery pipe and depending from the top wall of the outer cylinder within the inner cylinder, said tube terminating in spaced relation to said outlet port, an outlet valve disk seated over said port, a coil spring supported on the lower end of said tube and holding the outlet valve yielding to its seat, an outwardly seating valve for the submerged inlet of the chamber, and an air pipe leading into said chamber with pumping means supplying alternate suction and pressure impulses to actuate said valves and force liquid from the chamber into the delivery pipe.

2. In a liquid elevating system which includes a liquid supply, a chamber having an inlet sub-

merged therein and a delivery pipe leading upwardly therefrom, said chamber comprising an outer cylindrical body having a top wall, an inner cylinder suspended in the outer cylinder in spaced relation thereto and having an outlet port in its lower end, a delivery tube connected with said delivery pipe and depending from the top wall of the outer cylinder within the inner cylinder, said tube terminating in spaced relation to said outlet port, an outlet valve disk seated over said port, a coil spring supported on the lower end of said tube and holding the outlet valve yieldingly to its seat, a bottom wall for said chamber in which the said submerged inlet is located directly below said outlet port with an upstanding annular flange surrounding said inlet as a valve seat therefor, an inlet valve disk on said seat, an annular flange depending from the inner cylinder in spaced relation to said inlet valve disk with a spring coiled about said flange and holding the inlet valve yieldingly seated, and an air pipe leading into said chamber with pumping means supplying alternate suction and pressure impulses to actuate said valves and force liquid from the chamber into the delivery pipe.

3. In a liquid elevating system as defined in claim 2, said outer cylinder having a downwardly facing annular shoulder against which said bottom wall is normally seated, and spring means holding said bottom wall to said seat, whereby said bottom wall serves as a relief valve adapted to yield to release excessive air pressure in the chamber.

4. In a liquid elevating system which includes a chamber having an outwardly seating inlet valve and an inwardly seating outlet valve, a delivery pipe controlled by the latter valve and

an air pipe leading to said chamber, a pump comprising a cylinder and a piston reciprocable therein creating alternate pressure and suction impulses, said cylinder having a continuously open port into which the air pipe is connected and through which pressure and suction impulses are transmitted to said chamber to actuate the valves thereof and elevate liquid therefrom through the delivery pipe, means automatically supplying air to the air pipe during the suction impulses to replace air expelled therefrom by the pressure impulses, and means providing a delay in the reciprocation of the piston at the end of each suction stroke to facilitate operation of the valves in said chamber.

5. In a liquid elevating system which includes a chamber having an outwardly seating inlet valve and an inwardly seating outlet valve, a delivery pipe controlled by the latter valve and an air pipe leading to said chamber, a pump comprising a cylinder and a piston reciprocable therein creating alternate pressure and suction impulses, said cylinder having a continuously open port into which the air pipe is connected and through which pressure and suction impulses are transmitted to said chamber to actuate the valves thereof and elevate liquid therefrom through the delivery pipe, means automatically supplying air to the air pipe during the suction impulses to replace air expelled therefrom by the pressure impulses, means to reciprocate the piston comprising a cam for driving it in one direction and spring means to return it, said cam being arranged to provide a delay in the reciprocation of the piston at the end of each suction stroke to facilitate actuation of the valves in said chamber.

LEWIS PENGILLY.
